UNITED STATES PATENT OFFICE.

WILLIAM PERTIMAN SPRAGG, OF MOBERLY, MISSOURI.

SHEARS.

No. 823,816.

Specification of Letters Patent.

Patented June 19, 1906.

Application filed October 3, 1905. Serial No. 281,118.

To all whom it may concern:

Be it known that I, WILLIAM PERTIMAN SPRAGG, a citizen of the United States, and a resident of Moberly, in the county of Randolph and State of Missouri, have invented new and Improved Shears, of which the following is a full, clear, and exact description.

This invention relates to shears; and it consists, substantially, in the details of construction and combinations of parts herein-after more particularly described, and pointed out in the claims.

The invention has reference more especially to shears for cutting or trimming bolts, wires, wire nails, and the like; and one of the principal objects of the invention is to provide shears of this kind of an embodiment to overcome numerous disadvantages and objections encountered in the use of many other shears of the kind hitherto devised.

A further object is to provide shears of the character specified which is simple in construction and comparatively inexpensive to manufacture besides being thoroughly effective and reliable in use and possessing the capacity for long and repeated service.

The above and additional objects are attained by means substantially such as are illustrated in the accompanying drawings, in which—

Figure 1 is a side view of shears embodying my improvements, and Fig. 2 is a view of my improved shears looking at the same from either side of Fig. 1, the full lines indicating the closed position of the handles and blades and the dotted lines the open position thereof.

Before proceeding with a more detailed description it may be stated that in the form of my improvements herein shown I employ shears of the character referred to comprising specially-constructed handles or levers having special coöperating movable fulcrums, together with special connections at such fulcrums for maintaining the desired relation therebetween. Specially-constructed blades are employed for the shears, having the inner ends thereof in movable relation with the corresponding ends of the handles or levers, the opposite edges of the blades or levers being parallel and beveled or sharpened for a suitable proportion of length of the blades or levers from their outer ends, special means being employed for maintaining the cutting portions of the blades or levers in movable relation with each other.

Reference being had to the drawings by

the designating characters thereon, 1 represents my improved shears in entirety, the same comprising handles or levers 2, which are curved outwardly from each other in the direction of the free ends thereof, as shown, such ends being provided with grips or hand-grasps 3 for enabling the operator to grasp the shears for the purpose of manipulating the same. The inner ends of said handles or levers 2 are formed with short arms 4, which when the handles or levers 2 are brought together as far as permitted by a stop 5, applied to one of them, are divergent, as shown in Fig. 2, each of said arms being provided with integral parallel jaws 5^a, spaced from each other for a suitable distance and supporting between them a pin or rivet 6, on which is loosely or pivotally mounted the inner end of one of the blades 7 of the shears. The inner ends of the blades are normally slightly divergent in the direction of the handles or levers, while for a suitable distance from the outer ends of said blades the inner or opposite parallel edges 8 thereof are beveled or sharpened for the purpose of effecting the cutting or trimming of bolts, wires, and similar metallic objects, as will presently be explained. Also for a suitable distance from the outer ends thereof the blades 7 are movably connected together at either side by means of parallel links 9, said links being themselves connected together by means of pins or rivets 10, extending through suitable openings therefor in the said blades 7.

The inner ends of the handles or levers 2 are provided with coöperating intermeshing toothed segments 11, the teeth of which engage each other, as shown in Fig. 2, said segments constituting practically movable fulcrums between the said handles or levers 2. Parallel links 12 are employed for movably connecting together the inner ends of the handles or levers 2, so as to maintain the toothed segments in operative relation to each other, these parallel links 12 being themselves connected together by means of pins or rivets 13, passing through suitable openings therefor in the segments and constituting practically the working centers for said segments.

The stop 5 for limiting the extent to which the handles or levers 2 may be brought together in operation is preferably provided with a set-screw 14, so as to enable adjustment thereof to be made in conformity with the widening of the normal distance between

the beveled or sharpened edges 8 of the blades either due to wear or grinding of such edges or other causes.

From the foregoing it will be seen that by taking hold of the grips or hand-grasps 3 and pulling the handles or levers 2 apart the toothed segments will roll upon each other, thereby carrying the normal divergent short arms 4 of the handles or levers practically in parallelism, as shown in dotted lines in Fig. 2, thereby causing the blades 7 to swing upon the centers provided therefor by the pins or rivets 10. In this way the cutting edges of the blades are caused to be separated a sufficient distance to enable the bolt, wire, or other object to be inserted therebetween for the purpose of trimming or cutting off the same, as may be desired. To effect the cutting of the object, the handles or levers 2 are carried together with a sufficient amount of force, whereupon the operation of the parts is caused to take place reversely to that first above described, as will be readily understood.

Having thus described my invention, I claim as new and desire to secure by Letters Patent—

1. Shears, comprising handles having intermeshing teeth and pivotally connected with each other intermediate of their ends, and blades pivotally connected with each other and with the inner ends of the handles.
2. Shears, comprising handles having in-

termeshing teeth and pivotally connected with each other intermediate of their ends, 35 and blades pivoted to the inner ends of the handles and having a link connection with each other adjacent their cutting edges.

3. Shears, comprising lever-handles having intermeshing toothed segments, links 40 pivotally connecting the lever-handles, blades pivoted to the inner ends of the lever-handles, and links pivotally connecting the blades, adjacent to the cutting edges thereof.

4. Shears, comprising lever-handles provided adjacent to their inner ends with intermeshing toothed segments, parallel links pivotally connecting the inner ends of the lever-handles, blades having diverging inner ends pivoted to the inner ends of the lever-handles, and parallel links pivotally connecting the outer ends of the blades. 45

5. Shears, comprising lever-handles having intermeshing teeth and pivotally connected with each other intermediate of their 55 ends, blades pivotally connected with each other and with the inner ends of the lever-handles, and an adjustable stop on one of the lever-handles.

In testimony whereof I have signed my 60 name to this specification in the presence of two subscribing witnesses.

WILLIAM PERTIMAN SPRAGG.
